UNITED STATES PATENT OFFICE

2,245,026

INTERLOCKING FOR CONTAINERS

Philip Zalkind, New York, N. Y.

Original application October 16, 1933, Serial No 693,841. Divided and this application February 2, 1939, Serial No. 254,178

11 Claims. (Cl. 312—111)

This invention is a division of my United States application Serial No. 693,841, filed October 16, 1933, now U. S. Patent No. 2,233,906, issued March 4, 1941, and relates to novel structural members and more particularly relates to collapsible containers and novel securing and reinforcing means therefor including members for interlocking vertically and horizontally adjacent containers.

In containers of the type described in my application Serial No. 690,360, filed September 21, 1933, now U. S. Patent No. 2,118,011, issued May 17, 1938, I described collapsible containers having vertical and horizontal end reinforcements of various types. Likewise, in my U. S. Patent No. 2,233,906, of which this case is a true division, I have disclosed various modified types of container reinforcements.

It is now an object of this invention to provide means associated with collapsible containers of the foregoing types and particularly with the reinforcements thereof for interlocking vertically and horizontally adjacent containers.

Further objects and uses of this invention will be apparent in the following description and drawings in which:

Figure 1 is a view in perspective of one form of metallic vertical reinforcement for my container showing pockets for receiving the interlock.

Figure 2 is a view in perspective of an assembled container and drawer showing the vertical reinforcement of Figure 1 in place thereon.

Figure 3 is a view in perspective of one form of interlock bar.

Figure 4 is a view in perspective of an end of a portion of a stack of containers showing the interlock bar and the reinforcement of Figure 1 and the cooperation between them.

Figure 5 is a cross-sectional view taken on line 5—5 of Figure 4 showing a modified type of interlock.

Figure 6 is a view in perspective of an end of a portion of a stack of containers showing a combination of the forms of Figures 3 and 5.

Figure 7 is a view in perspective of the form of interlock member used in Figure 6.

Figure 8 is a cross sectional view taken on line 8—8 of Figure 6.

Figure 9 is a view in perspective of the container of Figure 2 showing its form preparatory for collapse.

Figure 10 is a view in perspective of the simplified interlocking means of Figures 4 and 5.

Referring now to Figure 1, I have here illustrated a type of reinforcement for the front end of a collapsible container useful in connection with the containers of my above mentioned application.

As shown, the member 35 is provided with a

plurality of securing prongs 36, 37, 38 and 39 formed by punching these prongs from the metal to protrude at right angles to the surface of the metal. Each prong consists of substantially triangularly shaped members having curved sides and base to secure member 35 to the wall of any member such as the wall of a casing near its edge as will be described in detail hereinafter. Two pockets, straps or sockets 43 and 44 formed by slitting and embossing the metal are located at the opposite ends of member 35 with open ends facing the adjacent end of the casing and are provided for the purpose of interlocking adjoining casings.

This type of reinforcement is that specifically described in my U. S. Patent No. 2,233,906, the said reinforcement being bendable along slots 51 and 52 as therein described for erecting the container, the said reinforcement also providing the rabbet 45 and the friction reducing means 47.

The interlocking device may as readily be applied to and constructed in connection with the reinforcements of my container, U. S. Patent No. 2,118,011 or in connection with any other type of reinforcement which may be used on a collapsible container.

The casing 108, Figure 2, is provided with vertical reinforcing members 109 and 110 fabricated in a manner described in detail in connection with Figure 1 and having the same prongs 36 and 37 as shown in that figure, the pocket or socket formation 43 and 44 receiving the interlocking member, slit formations 51 and 52 forming the predetermined bending line at the edge of the casing, the embossing 45 which provides a rabbet formation, the roller 47 mounted on a pin 46 for rotation thereabout, horizontal reinforcing members 111 at the top and bottom of the front edge of the casing, which extend from one of the reinforcing members 109 to the opposite reinforcing member 110.

Horizontal members 111 form a bearing for angle wire 112 having two sections 113 and 114 at right angles to each other. Angle wire 112 is arranged adjacent to the horizontal edges of the front wall of the casing 108 and when the horizontal reinforcing member is slipped into place as shown in Figure 2, it secures the angle wire 112 in position and forms a bearing therefor, about which one section or leg 113 may be revolved. Angle wire extensions from both the right and left-hand ends of both top and bottom horizontal reinforcing members 111 are provided.

In practice, the casing is shipped collapsed, with the fabricated member 109 extending in a plane as shown in Figure 1, that is to say, not bent along the predetermined bending lines formed at 51 and 52. At the point where the casing is to be used, the angle wires 112 are rocked in their bearings until the vertical por-

tion or leg section 114 of each of these angle wires is against the vertical edge at the front of the casing. Members 109 and 110 are then bent along their predetermined bending lines encasing the vertical legs or portions 114 of the angle wires 112. Secured to the rear edge of the casing 108 are reinforcing member 115 and 116, the details of which are described in my application Serial No. 693,841.

In Figure 3 I have shown the simplest form of interlock comprising a metal member 171 having an embossed central portion at 172 in which a lug is punched, as shown at 173. The ends 174 and 175 of the member 171 are arranged to seat themselves in the pockets or sockets 176 and 177, Figure 4, which are formed on the reinforcing members 178 and 179 of adjacent casings and are similar in construction to that described in connection with the embossed pockets 43 and 44 of Figure 1.

In actual practice, one end of member 171 is first inserted in the pocket 177 of the reinforcing member 179 of the lower casing, the pocket 176 of the reinforcing member 178 on the upper casing is then brought next to the upper edge of the interlocking member, and the end 175 is permitted to slip into place as shown in Figure 4. This interlock arrangement may of course be used at both the front and rear of the casing.

In another form of interlock, especially suitable for the rear of the casing, I provide a substantially U-shaped member 181, Figure 10, having turned-in ends 183 and 184. Member 181 is adapted to be slipped over the horizontal reinforcing members on the rear walls of the casing, of the form to be described hereinafter. Thus, as illustrated in Figures 4 and 5, the member 181 encases the two reinforcing members 185 and 186 and the turned-in ends form locking lugs for this interlock.

In a further adaptation of my interlock for securing not only the vertical column of casings, but also adjacent horizontal casings, I provide a substantially U-shaped member 191 having lugs 192 and 193 punched therein and having an extension 193' integral with the U-shaped member 191. Extending transversely of said U and integral with the extension 193' is a flat member 195 having lugs 196 and 197 punched therein, (see Figure 7). As shown in Figures 6 and 8 the U-shaped portion 191 is slipped over the horizontal reinforcing members until the lugs 193 and 194 engage the rear of the reinforcing member and lock the interlock in position. The extension 195 brings the portion 195 in surface contact with the vertical reinforcing members of the two adjacent casings being interlocked. The lug 196 now provides a receiving pocket for corresponding lug 197' on the interlock secured to the next adjacent column of casings and the opening formed by the lug 197 in turn forms a pocket for the corresponding lug 196' of the adjacent interlock. Thus, the U-shaped member 191' of the adjacent interlock is provided with the transverse member 195' having lugs 196' and 197' formed thereon which, as shown in Figure 7, cooperate with the lugs 196 and 197.

In Figure 9 I have shown a completed setup of the casing as it is received in shipping and before complete assembly. In Figure 9, the casing is shown after it has been received in shipment and turned on its scored lines into the form of a shell. The angle wires 203 protruding from the horizontal reinforcing members 204 are in

position to be turned in their bearings to a position adjacent to the vertical front edges of the casing so that as the vertical reinforcing member 205 is turned on its predetermined bending line 206 and the vertical reinforcing member 207 is turned on its predetermined bending line 208, they will encase the angle wires 203. The rear end thereof is formed as described in my parent application.

It is obvious, of course, that when the interlock member of Figure 3 is used, for instance as shown at Figure 4, the lug 173 thereof may be utilized in exactly the same manner as lugs 196 and 197 of member Figure 7 to form a "horizontal" interlock, the lugs of adjacent members 175 being inverted with respect to each other in the manner as shown in connection with the lugs of member 191 in Figure 8 to interlock the casings horizontally.

Where the pockets or sockets 43 and 44 are open at each end as they may well be, the shoulder 172 of member 175 of Figure 3 provides an abutment for retaining the interlocking member in position.

As seen in Figure 4, the interlock member connects vertical reinforcements in such a manner as to turn superjacent reinforcements into virtually a single column for transmitting loads from the uppermost casing of the stack to the base of the stack.

In the above I have described my invention by illustrating preferred adaptations thereof, but it will be obvious that it may take other forms and I do not wish to be limited except as set forth in the appended claims.

I claim:

1. A stack of casings to be shipped in knocked-down condition each casing comprising side, top and bottom members; an open front end; reinforcing members for said open front end; separable members; means consisting of pockets formed on the outer side of the reinforcing members for securing said separable members to reinforcing members of adjacent casings for interlocking said casings, and lugs formed from and integral with said separable members whereby said separable members on horizontal adjacent casings are interlocked by the interengagement of said lugs.

2. A stack of casings to be shipped in knocked-down condition each casing comprising side, top and bottom members; an open front end; vertical metallic reinforcing members for the sides of said open front end and securely affixed to the side wall members with the casing in the knocked-down condition; separate horizontal reinforcing members; stacking members detachable and removable from said vertical reinforcing members and means consisting of pockets formed on the outer side of said vertical reinforcing members into which the ends of said detachable members snugly fit for securing said detachable members to reinforcing members of vertically adjacent casings for interlocking said casings.

3. In combination, a file having a casing provided with a lateral socket element adjacent to the top wall thereof, and a stacking member having a lower portion adapted to be inserted within said socket element and an upper portion adapted to extend above the upper edge of the casing and be received in a similar socket element adjacent to the bottom wall of a casing stacked above the first casing, said member including a wider, intermediate portion having shoulders for

engaging the walls of the socket element at the top of the first casing to limit the downward movement of the stacking member within said stacking element, and to be engaged by the socket element at the bottom of the superposed casing so as to assist in transmitting the pressure from the upper to the lower casing through the socket elements, said stacking member having integral means shaped for interlocking engagement with similar means on a stacking member positioned on an adjacent column of files for holding the columns against displacement in at least one direction.

4. A plurality of individual files each having a casing and drawer and arranged in vertical columns and horizontal rows, each casing having socket elements at the front corners thereof, stacking members each detachably received within the socket element at the top corner of one casing and within the socket element at the bottom corner of the superposed casing and thus connecting two adjacent vertically stacked casings by way of such socket elements, said stacking members provided with projecting means which interlock to limit horizontal movement of one stacking member relative to the other and hold the vertical columns of casings against endwise displacement, the said interlocking stacking members being of identical construction but reversed with respect to each other.

5. A stacking member for individual files arranged in vertical columns, said member having end portions adapted to engage suitable anchoring means at the top of one casing and at the bottom of a superposed casing and having an intermediate outwardly projecting portion shaped to interlock with the intermediate portion of an identical stacking member reversed with respect to said first member to limit movement of such members relatively to each other at substantially the same horizontal level.

6. A stacking member for individual files arranged in vertical columns, said member having end portions adapted to engage suitable anchoring means at the top of one casing and at the bottom of a superposed casing and having an intermediate outwardly projecting portion shaped to interlock with the intermediate portion of an identical stacking member reversed with respect to said first member to limit movement of such members relatively to each other at substantially the same horizontal level, the intermediate portion of the stacking member being shaped so as to be capable of at least limited relative vertical movement with respect to a second member horizontally interlocked therewith.

7. A stacking member for individual files adapted to be arranged in vertical columns and horizontal rows, said member having end portions adapted to engage suitable anchoring means at the top of one casing and at the bottom of a superposed casing and having an intermediate portion comprising an outwardly bent lug, and a space on the inner side of said lug to enable the lug of a second similar member to interengage with the lug of the aforementioned member.

8. A stacking member for individual files adapted to be arranged in vertical columns and horizontal rows, said member having end portions adapted to engage suitable anchoring means at the top of one casing and at the bottom of a

superposed casing and having an intermediate portion comprising an outwardly bent lug, and a space on the inner side of said lug to enable the lug of a second similar member to interengage with the lug of the aforementioned member, the intermediate portion of the stacking member terminating at one side in a lug and at the other side being provided with a cut-out corresponding in width to a lug whereby identically constructed stacking members reversed with respect to each other can be brought close to each other with their outwardly bent lugs in interlocking relation to hold adjacent columns of vertical files against relative displacement in at least one direction.

9. In combination, a file having a casing provided with a socket element adjacent to the top wall thereof, and a stacking member having a lower portion adapted to be inserted within said socket element and an upper portion adapted to extend above the upper edge of the casing and be received in a similar socket element adjacent to the bottom wall of a casing stacked above the first casing, said member including an intermediate portion adapted to engage the socket element at the top of the first casing to limit the downward movement of the stacking member within said stacking element, and to be engaged by the socket element at the bottom of the superposed casing so as to assist in transmitting the pressure from the upper to the lower casing through the socket elements, said intermediate portion comprising a lug adapted to interengage with a symmetrically positioned stacking member on an adjacent column of files to hold the column against longitudinal displacement.

10. A stacking member for individual files adapted to be arranged in vertical columns and horizontal rows, said member having end portions adapted to engage suitable anchoring means at the top of one casing and at the bottom of a superposed casing and having an intermediate portion composed of outwardly bent, spaced members, the space between the members being slightly wider than a projection of a second similar member to enable the projection of said second similar member to interengage between the spaced members of the aforementioned member.

11. In combination, a file having a casing provided with a socket element adjacent to the top wall thereof, and a stacking member having a lower portion adapted to be inserted within said socket element and an upper portion adapted to extend above the upper edge of the casing and be received in a similar socket element adjacent to the bottom wall of a casing stacked above the first casing, said member including an intermediate portion adapted to engage the socket element at the top of the first casing to limit the downward movement of the stacking member within said stacking element, and to be engaged by the socket element at the bottom of the superposed casing so as to assist in transmitting the pressure from the upper to the lower casing through the socket elements, said intermediate portion including a plurality of spaced members adapted to interengage with a stacking member reversed with respect thereto on an adjacent column of files to hold the column against longitudinal displacement.

PHILIP ZALKIND.
